CLAIM

The ornamental design for a flower pot cover, as shown and described.

DESCRIPTION

FIG. 1 is a perspective view of our new flower pot cover design;

FIG. 2 is a reduced side elevational view thereof;

FIG. 3 is a reduced top plan view thereof;

FIG. 4 is a reduced bottom plan view thereof;

FIG. 5 is a reduced side elevational view of the design of FIG. 1, the only difference being the angle of the skirt;

FIG. 6 is a reduced side elevational view of the design of FIG. 1, the only difference being the angle of the skirt;

FIG. 7 is a perspective view of another embodiment of our new flower pot cover design;

FIG. 8 is a reduced side elevational view thereof;

FIG. 9 is a reduced top plan view thereof;

FIG. 10 is a reduced bottom plan view thereof;

FIG. 11 is a reduced side elevational view of the design of FIG. 7, the only difference being the angle of the skirt; and, FIG. 12 is a reduced side elevational view of the design of FIG. 7, the only difference being the angle of the skirt.

The flower pot cover has no substantial thickness.

The characteristic feature of the design resides in the specific pleating arrangement comprised of the parallel disposition of the exterior folds in combination with the interior V-shaped folds all as best shown in FIG. 1.
